UNITED STATES PATENT OFFICE.

IVAN WIDE, OF CHICAGO, ILLINOIS.

LOOSE-LEAF BINDER.

SPECIFICATION forming part of Letters Patent No. 766,304, dated August 2, 1904.

Application filed November 9, 1903. Serial No. 180,454. (No model.)

To all whom it may concern:

Be it known that I, IVAN WIDE, a citizen of the United States, residing at Chicago, in the county of Cook and State of Illinois, have invented certain new and useful Improvements in Loose-Leaf Binders, of which the following is a specification.

The object of this invention is the production of a loose-leaf binder embodying the various improvements hereinafter pointed out.

In the accompanying drawings, Figure 1 is a top plan view, partly in section, of a binder embodying the features of my invention. Fig. 2 is a transverse vertical section on dotted line 2 2 of Fig. 1. Fig. 3 is a longitudinal vertical section through the binder, taken on dotted line 3 3 of Fig. 1.

In the embodiment herein shown a curved back portion A extends throughout the length of the binder and is provided at its ends with integral end pieces A' and A² for closing the ends of the binder, said end pieces extending at substantially a right angle with the back portion A. At each end of each of the end pieces A' A² is formed a stop-flange A³, and the end piece A' has an opening A⁴ therethrough for receiving an operating-key to be hereinafter more fully described.

Two side members B and C, adapted to be moved toward and from each other, lie between the end pieces A' and A² and are provided with side flanges B' and C' and with rigid end pieces B² and C², respectively. Near their opposite ends the side members are also provided with transverse integral sleeves B³ and C³, internally screw-threaded, the sleeves B³ having right-hand threads and the sleeves C³ left-hand threads. Upon the inner faces of the flanges B' and C' are rigidly mounted four pairs of holding-pins, one pin of each pair being tubular to telescope with the coinciding pin upon the opposite flange. Each flange carries two solid pins B⁴ C⁴ and two tubular pins B⁵ C⁵, the length of the pins being such that the pins of the pairs are not separated in the operation of the binder. Upon the outer side of each of the side flanges B' C', near the upper edge thereof, is a series of integral cover-attaching lugs or ears B⁶ C⁶, the lugs upon each side being provided with alined

openings B⁷ C⁷. Each of the end pieces B² C² has at one edge an integral stop-flange B⁸ C⁸, adapted to engage one of the similar stop-flanges A³ upon the adjacent end piece A' A² for limiting the outward movement of the side members B and C.

A housing D is secured to the inner side of the back portion A, near each end thereof, each of said housings comprising two sections D', formed, preferably, of sheet metal and secured to the back portion A by means of angle-pieces D², riveted to said sections D' and the back portion. The sides of the housings D are provided with openings D³, alined with the screw-threaded sleeves B³ C³ of the side members B and C, and in their opposite ends said housings have alined openings D⁴.

A shaft E, provided at its opposite ends with right and left hand screw-threads, respectively, lies within the openings D³ of the housings D, with its ends extending into the correspondingly screw-threaded sleeves B³ C³ of the members B and C. Within the housings D each of the shafts E carries a worm-wheel E', fixed on its shaft. 75

F refers to an operating-shaft extending throughout substantially the entire length of the binder and rotatably supported within the openings D⁴ of the housings D. This shaft within each of the housings D is provided with a worm F', adapted to mesh with the worm-wheel E' in said housing.

The end of the shaft F adjacent to the opening A⁴ in the end piece A' is squared to receive a socket-key G for rotating said shaft, 85 said key being adapted to be inserted into said opening A⁴.

Covers H of the ordinary description are hinged to the side members B and C in any suitable manner. In this instance I have pivotally mounted them upon the lugs B⁶ C⁶ of said side members, each of said covers being provided with notches H' to receive said lugs and with a pintle H², extending through the lugs and the cover. 90

A rotation of the worm-shaft F communicates rotatory motion to the shafts E for moving the side members B and C toward or from each other, according to the direction of rotation of said shaft F. 100

In constructing this binder the embodiment herein shown may be changed in various details without departing from the spirit and scope of my invention, wherefore I desire to have it understood that I do not limit myself to the particular form herein illustrated and described.

I claim as my invention—

1. In a loose-leaf binder, in combination, a back portion curved in transverse section; two side members adapted to have a transverse sliding movement with relation to said back; a transverse shaft oppositely screw-threaded at its opposite ends to have a screw-thread engagement with said side members; a worm-wheel fixed on said transverse shaft; an operating-shaft extending along the longitudinal center line of said back portion within the curve thereof; and a worm fixed on said operating-shaft and adapted to engage the worm-wheel on said screw-threaded shaft.
2. In a loose-leaf binder, in combination, a back portion curved in transverse section; two side members adapted to have a transverse sliding movement with relation to said back; a housing secured to said back portion upon the inner concave side thereof and near the longitudinal center line thereof; a shaft rotatably mounted within said housing, having a worm-wheel fixed thereon within the housing and being oppositely screw-threaded at its opposite ends to have a screw-thread engagement with said side members; an operating-shaft extending longitudinally of said back portion and adapted to lie within the curve of said back portion and being rotatively mounted in said housing; and a worm fixed on said operating-shaft within said housing and adapted to engage the worm-wheel on said screw-threaded shaft.
3. In a loose-leaf binder, in combination, a back portion curved in transverse section and having end pieces; two side members adapted to lie between the end pieces of said back portion and to have a transverse sliding movement with relation to said back, each side member also having an integral internally-screw-threaded sleeve, a side flange, and inwardly-extending telescoping holding-pins; a shaft extending transversely of and rotata-

bly mounted on said back portion, said shaft being oppositely screw-threaded on its opposite ends to engage the screw-threads in said sleeves; a worm-wheel fixed to said shaft; and an operating-shaft extending longitudinally of said back portion and lying within the concave side of said back portion beneath said screw-threaded transverse shaft and having fixed thereon a worm for engaging the worm-wheel on said screw-threaded shaft.

60

4. In a loose-leaf binder, in combination, a back portion curved in transverse section and having end pieces; two side members adapted to lie between the end pieces of the back and have a transverse sliding movement with relation to said back, each side member also having an integral internally-screw-threaded sleeve, a side flange, inwardly-extending telescoping holding-pins upon the inner side of said flange, and perforated lugs upon its outer side adapted to receive a hinged cover; a housing secured to said back portion upon the inner concave side thereof and near the longitudinal center line thereof; a shaft rotatably mounted within said housing, having a worm-wheel fixed thereon within the housing and being oppositely screw-threaded at its opposite ends to engage the screw-threads in said sleeves; an operating-shaft extending longitudinally of said back portion and adapted to lie within the curve of said back portion and being rotatably mounted in said housing; and a worm fixed on said operating-shaft within said housing and adapted to engage the worm-wheel on said screw-threaded shaft.

75

5. In a loose-leaf binder, in combination, a back portion provided with integral end pieces, said end pieces having stop-flanges at their ends; and two side members slidably supported with relation to said back portion, said side members having integral end pieces provided with stop-flanges adapted to engage the stop-flanges upon the end pieces of the back portion, for limiting the outward movement of said side members.
